(57) CLAIM

The ornamental design for a shoe upper, as shown and described.

DESCRIPTION

FIG. 1 is a front perspective view of a shoe upper showing my new design;

FIG. 2 is a rear perspective view thereof;

FIG. 3 is a side view thereof;

FIG. 4 is a front perspective view of a shoe upper showing a second embodiment of my new design;

FIG. 5 is a rear perspective view thereof; and,

FIG. 6 is a side view thereof.

The broken lines immediately adjacent to the shaded area represent unclaimed boundaries of the design. The broken lines showing a disclaimed line, seven eyelet regions and the remainder of the shoe in FIGS. 1-6, as well as additionally disclaimed stripes in FIGS. 4-6, are for environmental purposes only and form no part of the claimed design.
